UNITED STATES PATENT OFFICE.

OTIS A. MYGATT, OF NEW YORK, N. Y.

DESIGN FOR AN ILLUMINATOR.

No. 37,825.

Specification for Design.

Patented Feb. 13, 1906.

Application filed July 14, 1905. Serial No. 269,735. Term of patent 14 years.

To all whom it may concern:

Be it known that I, OTIS A. MYGATT, a citizen of the United States, residing at New York, in the county of New York and State of New York, have invented a certain new, original, and ornamental Design for an Illuminator, of which the following is a specification, reference being had therein to the accompanying drawings, forming part thereof.

Figure 1 is a side elevation of the illuminator. Fig. 2 is a perspective view as seen from a plane a little below the illuminator.

The socket or holder of the illuminator is of opaque material. The bell is of transparent glass. The visible portion of the bulb is 15 of translucent glass.

I claim—

The ornamental design for an illuminator, as shown and described.

OTIS A. MYGATT.
